D. C. JANNOPOULO

PROTECTIVE DEVICE FOR SAFE TIME CLOCKS

Filed May 14, 1924

INVENTOR

DEMOSTHENES C. JANNOPOULO,

by Adam E. Fisher. Attorney.

UNITED STATES PATENT OFFICE.

DEMOSTHENES C. JANNOPOULO, OF ST. LOUIS, MISSOURI.

PROTECTIVE DEVICE FOR SAFE TIME CLOCKS.

Application filed May 14, 1924. Serial No. 713,232.

To all whom it may concern:

Be it known that DEMOSTHENES C. JANNOPOULO, a citizen of the United States, residing at St. Louis, State of Missouri,

5 has invented certain new and useful Improvements in Protective Devices for Safe Time Clocks, of which the following is a specification.

This invention is in the way of a protective device for the time clocks of safes and vaults. It is a well known fact that the usual or standard time clocks may be "speeded up" by projecting a magnetic field angularly or obliquely across the clock 10 mechanism, which results in accelerating the oscillations of the balance wheel.

It is the object of the present invention, therefore, to supply a relatively simple and yet effective braking device which may be 15 readily mounted in connection with any standard time clock and which will operate to prevent the stated acceleration of the balance wheel thereof.

In the drawing 25 Figure 1 is a perspective view of the balance wheel of a time clock with this device operatively positioned in relation thereto;

Figure 2 is a side view of the assembly 30 shown in Figure 1;

Figure 3 is a top or plan view;

Figure 4 is a transverse sectional view through a portion of the balance wheel and through the braking mechanism.

35 This improvement is designed for use upon a conventional chronometer or time clock. Such a time clock includes a balance wheel 1 having a cross bar 2 whereby it is pivoted at 3 to the bracket 4 which supports the wheel within the clock frame 40 (not shown) and in operative position relative to the rest of the clock mechanism (not shown).

In carrying out this invention there is 45 pivoted at 5, in close proximity to the balance wheel 1, a composite metal bar 6, which is made up of a thin strip of brass 7 having a thin strip of steel 8 mounted upon one end thereof. The bar 6 is nicely 50 balanced upon its pivot points 5, and is preferably, though not necessarily, slightly bowed or bent at its center point 9, for a purpose to be later explained. A pivot pin 10 is secured transversely to the bar 6 at 55 the center point 9, and the ends of this pin have pivotal bearings at the points 5

in the bracket 11, as stated, and the bracket 11 is in turn secured to the clock frame or case, in any conventional manner (not shown).

60 It will be noted that the axis of the pivot pin 10 is mounted obliquely relative to the plane of the balance wheel 1, as clearly shown in Figure 4. At each end of the bar 6 is mounted an angular rubber stop 65 12, adapted to frictionally impinge upon the periphery of the said balance wheel as either end of the bar 6 is tilted obliquely down toward the wheel under the influence of magnetism. The bar 6 is mounted to 70 move easily in its bearings 5, so as to turn even in a weak magnetic field, and a delicate coil spring 13 is set over one end of the pin 10 with one end attached to the pin and the other end to the bracket 11, and 75 serves to normally hold the bar 6 out of engagement with the balance wheel 1.

The operation of the device is as follows: A magnetic field, when thrown in the region 80 of the balance wheel 1, acts upon the steel strip 8 at one end of the bar 6, thereby causing the bar 6 to turn in its bearings until one of the frictional stops or shoes 12 strikes upon the periphery of the balance wheel 1 and retards the oscillation of that 85 wheel. At the same time the said magnetic field tends to speed up the oscillations of the balance wheel, above its normal rate. Therefore, the pivoted bar 6 acts either as 90 a governor to keep the wheel going at its normal rate, when a magnetic field is directed upon it, or to reduce the balance wheel to an abnormally slow rate of oscillation, thereby frustrating any unauthorized attempts to speed it up abnormally by the 95 use of magnetism. The coil spring 13 acts to hold the bar 6 in a normal inoperative position and until the influence of a magnetic field is brought to bear upon it. The 100 bar 6 is bowed as stated, and is positioned askew relative to the plane of the balance wheel, in order to render it even more difficult to influence the speed of the balance wheel by means of magnetism, without at 105 the same time setting in operation the preventive agency of the bar 6 to counteract any accelerating effect of a magnetic field thrown across the clock. The reason for this is that a magnetic field must be thrown obliquely across the balance wheel in order 110 to accelerate its motion, while the bar 6, having the susceptible steel strip 8 at one

end thereof, is influenced whether the lines of force strike it either perpendicularly or obliquely. By mounting the bar 6 at an angle relative to the wheel 1, therefore, it is thought that the difficulty of an unauthorized attempt at speeding the balance wheel is increased.

While I have herein described a certain specific manner and method of constructing and assembling the elements of my invention, it is understood I may vary from the same in minor details, not departing from the spirit of my invention, so as best to construct a practical device for the purpose intended, as defined in the appended claims.

I claim:

1. In combination with a time clock and the balance wheel thereof, the said balance wheel being susceptible to acceleration under the influence of magnetism, a device for preventing such acceleration of the balance wheel, comprising a brass bar having a steel strip mounted at one end thereof, the bar being so pivoted at its center adjacent the balance wheel that the ends of the bar turning in its bearings will bear upon the periphery of the balance wheel.
2. In combination with a time clock and the balance wheel thereof, the said balance wheel being susceptible to acceleration under the influence of magnetism, a device for preventing such acceleration of the balance wheel, comprising a brass bar having a steel strip mounted at one end thereof, the bar being so pivoted at its center adjacent the balance wheel that the ends of the bar turning in its bearings will bear upon the periphery of the balance wheel; and frictional stops mounted upon the ends of the bar adapted to contact with the said periphery.
3. In combination with a time clock and the balance wheel thereof, the said balance wheel being susceptible to acceleration under the influence of magnetism, a device for preventing such acceleration of the balance wheel, comprising a brass bar having a steel strip mounted at one end thereof, the bar being so pivoted at its center adjacent the balance wheel that either end of the bar turning in its bearings will bear upon the periphery of the balance wheel; frictional

stops mounted upon the ends of the bar adapted to contact with the said periphery; and a coil spring set in the pivotal mounting of the said bar and adapted to hold the bar normally in inoperative position.

4. In combination with a time clock and the balance wheel thereof, the said wheel being susceptible to magnetic acceleration, a device to prevent such acceleration, the same comprising an arcuate bar pivoted by its center to turn in a plane oblique to the plane of the wheel and so that its ends in turn will impinge the periphery of the wheel, the said bar being composed of non-magnetic material at one end and of magnetic material at the other end.

5. In combination with a time clock and the balance wheel thereof, the said wheel being susceptible to magnetic acceleration, a device to prevent such acceleration, the same comprising an arcuate bar pivoted by its center to turn in a plane oblique to the plane of the wheel and so that its ends in turn will impinge the periphery of the wheel, the said bar being composed of non-magnetic material at one end and of magnetic material at the other end, the two ends of the bar being provided with frictional shoes adapted to bear upon the periphery of the wheel.

6. In combination with a time clock and the balance wheel thereof, the said wheel being susceptible to magnetic acceleration, a device to prevent such acceleration, the same comprising an arcuate bar pivoted by its center to turn in a plane oblique to the plane of the wheel and so that its ends in turn will impinge the periphery of the wheel, the said bar being composed of non-magnetic material at one end and of magnetic material at the other end, the two ends of the bar being provided with frictional shoes adapted to bear upon the periphery of the wheel; and means for holding the bar normally in balanced or inoperative position relative to the balance wheel.

In testimony whereof I affix my signature.

DEMOSTHENES C. JANNOPULO.
